Primary Examiner — Marie D. Fast Horse(74) *Attorney, Agent, or Firm* — Wagenknecht IP Law Group, PC**(57) CLAIM**

What is claimed is the ornamental design for a hub with stand for a mini computer, as shown and described.

DESCRIPTION

FIG. 1 is a front, top, left perspective view of a hub with stand for a mini computer showing our new design

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Wherein the broken lines depict portions of a hub with stand for mini computer that form no part of the claimed design.
